DESIGN FOR A BUTTON

Jesse S. Lichter, Lawrence, N. Y.

Application July 27, 1936, Serial No. 64,074

Term of patent 3½ years

To all whom it may concern:

Be it known that I, Jesse S. Lichter, a citizen of the United States of America, residing at Lawrence, county of Nassau, and State of New York, have invented a new, original, and ornamental Design for a Button, of which the following is a specification, reference being had to the accompanying drawing, forming part thereof, wherein—

Fig. 2 is a side elevational view of the button showing my new design.

I claim:

The ornamental design for a button substantially as shown.

JESSE S. LICHTER.
